UNITED STATES PATENT OFFICE.

MARSHALL W. GLEASON, OF NEW YORK, N. Y.

DESIGN FOR A GLASS SHADE.

SPECIFICATION forming part of Design No. 36,867, dated April 5, 1904.

Application filed February 24, 1904. Serial No. 195,114. Term of patent 3½ years.

To all whom it may concern:

Be it known that I, MARSHALL W. GLEASON, a citizen of the United States, residing at New York city, in the county of Kings and State of New York, have invented a new, original, and ornamental Design for a Glass Shade, of which the following is a specification, reference being had to the accompanying drawings, forming part thereof.

What I claim as new, and desire to secure by Letters Patent, is—

The ornamental design for a glass shade, as shown.

MARSHALL W. GLEASON.
